ATTORNEY

UNITED STATES PATENT OFFICE.

JOSEPH A. DUGAN, OF HOUSTON, TEXAS, ASSIGNOR OF ONE-HALF TO WILLIAM A. VINSON AND JOE CATHRINER, BOTH OF HOUSTON, TEXAS.

FUSE-PLUG.

1,268,824.

Specification of Letters Patent. Patented June 11, 1918.

Application filed October 1, 1917. Serial No. 194,252.

To all whom it may concern:

Be it known that I, JOSEPH A. DUGAN, citizen of the United States, residing at Houston, in the county of Harris and State 5 of Texas, have invented certain new and useful Improvements in Fuse-Plugs, of which the following is a specification.

This invention is a fuse plug and has for its principal object the production of a 10 safety structure which is suitable of prolonged usage.

Another object of this invention is the production of a fuse plug wherein a plurality of fusible wires are employed, there- 15 by permitting a new wire to be substituted in the circuit after the original wire has melted, thus prolonging the life and usage of the fuse plug.

A still further object of this invention is 20 the production of a fuse plug wherein one fusible wire is in the original circuit in which the fuse plug is used, although after this wire has melted due to an over voltage or charge, a new wire may be brought into 25 the circuit.

Another object of this invention is the production of a fuse plug, wherein the secondary wire is ordinarily not in use, although the ends thereof are connected 30 thereby allowing a trigger to be swung into engagement with one of the ends and into engagement with the contact plate, thereby bringing the auxiliary or secondary fusible wire into use.

With these and other objects in view, this invention relates to certain novel combinations, constructions, and arrangements of parts, as will be hereinafter fully described and claimed.

In the accompanying drawing I have disclosed one form of my invention, in which, Figure 1 is a central vertical section through the fuse plug, and

Fig. 2 is a bottom plan view of the fuse 45 plug.

Referring more specifically to the accompanying drawing by numerals it will be seen that 1 indicates the shell of the fuse plug. This shell 1 is preferably of an 50 elongated cylindrical construction as is the ordinary form of fuse plug now in use. This shell 1 has a conical portion 2 adjacent its lower end and this conical portion 2 is provided with a central opening 3, formed 55 therethrough, as shown clearly in Fig. 1,

The outer end of the shell 1 is normally closed by the usual transparent sheet 4, held in engagement therewith by the cap 5, secured upon the outer end of the shell 1. It should of course be understood, that the 60 shell 1 and the conical portion 2 are formed of some suitable insulating material, such for instance as glass or porcelain.

The usual threaded sleeve 6 is mounted upon the shell 1 and is formed of some suitable conducting material whereby when the fuse plug is screwed into a socket, it will be grounded upon a supporting structure by the sleeve 6.

The contact plate 7 is positioned upon the 70 lower or inner end of the conical portion 2, so as to normally close the concentric opening 3 formed in this conical portion as shown in Fig. 1. The contact plate 7 is provided with a plurality of inwardly extending 75 spurs 8 which spurs 8 are bent into engagement with the conical portion 2 upon the interior thereof, whereby the contact plate 7 will be firmly held in a set position. This contact plate 7 is provided with the 80 slot 9 formed therein and extending thereinto from its periphery to a point adjacent its center for purposes to be hereinafter set forth.

The usual fusible wire 10 has one end 85 grounded upon the plate 7, as shown at 11, while the opposite end of the fusible wire 10 is carried by the conductor 12 mounted upon the shell 1 of the fuse plug.

From the foregoing description it will be 90 seen that when this fuse plug is in use it should be screwed into a socket in the usual manner. Since the structure 12 will be grounded upon the socket by means of the sleeve 6, while the contact plate 7 will be in 95 its ordinary position, it is obvious that a circuit will be formed by the fusible wire 10. Of course, if a short circuit is experienced in the circuit in which the fuse plug is carried or if for any reason an over voltage 100 passes on to the fusible wire 10, this fusible wire 10 will melt as is the ordinary operation of the device whereby the circuit will be broken thus preventing any injury from the over charge.

The secondary fusible wire 13 has one end 105 grounded as indicated at 14 upon the shell 1, whereby it will be in contact with the sleeve 6. The conical portion 2 of the shell 1 is provided with the projecting lug 15 hav- 110

ing an eye 16 formed therethrough. The remaining end of the secondary fusible wire 13, projects through the eye 16 formed in the lug 15, as shown in Fig. 1. In this way 5 it is obvious that the secondary fusible wire will be firmly held in correct position for operation when necessary. The lower end of the second fusible wire 13 projects beyond the lug 15 for a spaced distance, as shown 10 in Fig. 1, whereby it will project to the slot 9 formed in the contact plate 7. Since the lug 15 is also formed of insulated material, it is obvious that notwithstanding the fact 15 that the fusible wire projects into the slot 9, it will not form a circuit.

The supporting ears 17 are formed upon the conical portion 2 in parallel relation and the trigger 18 is pivotally mounted upon the ears 17 and it will be understood that 20 this trigger 18 is formed of conducting material. Under normal conditions this trigger 18 is swung upwardly and maintained in an inoperative position, as clearly shown in the drawing.

25 When this fuse plug is engaged, it will be screwed into the usual socket, and at this time the trigger 18 is out of engagement with the contact plate 7 by being positioned as indicated in Figs. 1 and 2. If so desired, 30 it is obvious that the conical portion 2 may be provided with a notch 19 into which the trigger will partially pass whereby a binding action will be had upon the trigger for holding the same in an inoperative position. 35 If for some reason a short circuit or an overcharge causes the fusible wire 10 to melt, the fuse plug may be removed and at this time the trouble in the circuit may be corrected. The fuse may then be again inserted al- 40 though prior to this action the trigger 18 should be swung or pivoted upon the ears 17 so as to pass into the slot 9 as shown clearly in dotted lines in Fig. 1. As this trigger 18 is formed of conducting material it will 45 bear upon the contact plate 7 within the slot 9 and will also bear upon the projecting end of the second fusible wire 13. This action of the trigger 18 will form a circuit over the sleeve 6, the second fusible wire 13, the 50 trigger 18, and the contact plate 7. It is of course obvious that if some other over charge is experienced in the circuit in which the fused plug is used, the second fusible wire 13 will also melt, thus causing the fused 55 plug to positively protect the supporting structure of the fuse plug construction, although because of the use of the extra fusible wire, the life of the fuse plug will be greatly prolonged. 60 It will be obvious that many minor changes may be made in the detail construction of this invention without departing from the spirit of the device and for this reason it is not intended to limit the construction of this fuse plug to the specific 65

form herein shown but to include all such forms of the invention as properly come within the scope of the device as claimed.

What I claim is:—

1. In a fuse plug, the combination of a 70 supporting shell, a contact plate carried by said shell, a contact sleeve carried by said shell, a fusible wire connected to said sleeve and said plate, whereby a circuit may be formed, a second fusible wire connected to 75 said sleeve and carried by said shell at a point adjacent said plate, and means for closing the circuit between said second fusible wire and said plate after the first mentioned fusible wire becomes inoperative. 80

2. In a fuse plug, the combination of an insulated shell, a contact sleeve and a contact plate carried by said shell; a fusible wire connected with said plate and said sleeve, a second fusible wire connected to 85 said sleeve and also said shell, at a point adjacent said plate, and a movable trigger carried by said shell, said trigger being adapted to be moved into engagement with said plate and said second fusible wire after the first 90 mentioned fusible wire is melted.

3. In combination with a fuse plug, a primary circuit closing means carried by said shell and having contact terminals, an auxiliary means carried by said shell and being 95 engageable with said contact terminals at a time after the first mentioned means becomes inoperative.

4. In a fuse plug, the combination of a shell, a fusible wire carried by said shell, a 100 contact plate carried by said shell, said fusible wire being connected to said contact plate, said contact plate also having a slot formed therein, said shell having a lug formed thereon in alignment with the slot in 105 said contact plate, a second fusible wire carried by said shell, one end of said last mentioned fusible wire being supported by said lug, and means movably mounted upon said shell and passing into said slot after the 110 first mentioned movable wire has become inoperative; whereby the last mentioned means will be held by said plate in engagement with the second fusible wire. 115

5. In a fuse plug of the class described, 115 the combination of a shell, a contact sleeve carried by said shell, a contact plate carried by said shell, a fusible wire connected to said sleeve and said plate, said plate having a slot extending thereto, a second fusible wire 120 connected to said sleeve and at one end carried by said shell in alignment with the slot of said plate, and a trigger pivotally mounted upon said shell being adapted to be swung into said slot after said first mentioned fusible wire has become inoperative, thus causing said trigger to close the circuit between said second mentioned fusible wire and said plate. 125

6. In a fuse plug of the class described, 130

the combination of a shell, a sleeve carried by said shell, a contact plate carried by said shell, a fusible wire connected to said sleeve and said contact plate, said contact plate 5 having a slot extending thereinto, said shell having an internal lug formed in alinement with the slot in said plate, a second fusible wire connected to said sleeve and having one end carried by said lug and projecting into 10 said slot, and a trigger pivotally mounted upon said shell being adapted to be swung into engagement with said contact plate by fitting within said slot and also engage the end of said second fusible wire after the first 15 mentioned fusible wire has become inoperative.

7. In a fuse plug of the class described, the combination of a shell, a contact sleeve carried by said shell, a contact plate carried 20 by said shell, a fusible wire carried by said shell and engaging said sleeve and said contact plate, said plate having a slot extending

thereinto, said shell having a lug formed in alinement with said slot, a second fusible wire having one end connected to said sleeve 25 and the remaining end carried by said lug and extending into said slot, said shell having a notch formed therein, a trigger pivotally mounted upon said shell and normally fitting within said notch, thus being held in 30 an inoperative position, said trigger being capable of being swung from said notch after the first mentioned fusible wire has become inoperative, thus permitting the trigger to be moved into engagement with 35 said plate within said slot and at the same time engage the projecting end of said second mentioned fusible wire.

In testimony whereof I affix my signature in presence of two witnesses.

JOSEPH A. DUGAN.
